CLAIM

The ornamental design for a food cover, as shown and described.

DESCRIPTION

FIG. 1 is a right side elevational view of a food cover showing my new design, the left side elevational view being a mirror image thereof;

FIG. 2 is a top plan view thereof;

FIG. 3 is a front elevational view thereof;

FIG. 4 is a rear elevational view thereof; and,

FIG. 5 is a bottom plan view thereof.

The broken line showing of a food pot with handles is for illustrative purposes only and forms no part of the claimed design.

FIG. 2

FIG. 1

FIG. 3

FIG. 4

FIG. 5
